United States Patent Office.

ARTHUR FIELD, OF UPPER MARSH, LAMBETH, AND WILLIAM BRYER NATION, OF NO. 394 OLD KENT ROAD, ENGLAND; (SAID NATION ASSIGNS HIS RIGHT TO SAID FIELD.)

Letters Patent No. 88,779, dated April 13, 1869.

IMPROVED MODE OF ORNAMENTING CANDLES.

The Schedule referred to in these Letters Patent and making part of the same.

To all whom it may concern:

Be it known that we, ARTHUR FIELD, of the firm of John, Charles, and John Field, of Upper Marsh, Lambeth, in the county of Surrey, England, and WILLIAM BRYER NATION, of No. 394 Old Kent Road, in the county of Surrey aforesaid, have invented "an Improved Mode of Ornamenting Candles," and we do hereby declare that the following is a full and exact description of the said invention, reference being had to the accompanying drawings, and to the figures and letters marked thereon; that is to say—

One part of our invention consists in producing upon the surface of candles helical, straight, or other-shaped grooves, or recesses, and in filling such grooves, or recesses with wax, stearine, paraffine, or other suitable fatty matter, of a different color or colors from that of the candle.

For this purpose, we either insert into the mould of the candle, before this is cast, loose helical or straight pieces of metal, or other suitable material, which, when the candle is drawn from the mould, pass out with the same, and are then readily removed from the candle; or we cast the candle in the usual manner, and afterward pass it through a die or dies, so shaped as to cut the requisite helical or straight grooves upon it; or the candle, when cast, may be placed in a second mould, having a straight or helical slit in it, and by passing a cutting-edge along such slit, so as to cut a groove in the candle, and then turning the candle partly round, and cutting a second groove in the candle, and so on, the requisite helical or straight grooves may be produced. Or we cut such helical grooves upon candles by means of a machine to be hereafter described. Or, again, we form designs in relief upon the inner surface of folding-moulds, that is to say, moulds divided longitudinally into two or more parts, and held together in any suitable manner while the candle is being cast therein, after which the mould is opened out, and the candle, with recessed designs on its surface, is removed.

The candle prepared by any of the foregoing methods is then again placed into a mould, and the grooves, or recesses upon the same are filled in with melted wax or other material of the required color or colors.

When straight grooves are to be formed on the candle, instead of employing loose fillets to be placed in the mould, as before mentioned, these fillets may be fixed in the mould, and the candle will, in this case, have to be placed afterward in a different mould, without fillets, in order to fill in the grooves as described.

In some cases, the helical, straight, or other grooves, or recesses formed in the first instance may be left without being filled in as described.

Figure 1, on Sheet I of the accompanying drawings, shows, at A, a vertical section through an ordinary candle-mould, in which, before casting the candle, are

placed two or more loose helical fillets B, of metal, whalebone, or other suitable material, shown detached at Figure 2, the fillets being formed with a flat surface, resting close against the mould A, while the projecting surface is formed rounded, as shown.

The melted stearine, paraffine, or other material being run into the mould, the fillets B will become embedded in the candle, and when the latter is pushed out of the mould, the fillets B will pass out with it, and on being removed therefrom will leave helical grooves on the surface of the candle.

The candle is then replaced in the mould, and the helical passages formed by the grooves and the surface of the mould are then run in with melted paraffine or other material of a different color from that of the candle, thus producing a candle, as shown at Figure 3, with colored helical lines upon its surface.

For producing straight colored lines upon the candles, straight fillets B', shown detached at Figure 4, are placed in the mould, as at A', fig. 1, and in order to retain these fillets in their places in the mould, they are made to fit in corresponding grooves formed in the latter, so that when the candle is removed, and, after taking out the fillets, is reinserted in the mould, and the colored material is run into the small channels thus formed, a candle will be produced having upon its surface projecting straight fillets, of a different color from that of the candle, as shown at Figure 5.

As before stated, if it is desired to produce straight colored lines upon the candle, not projecting from its surface, the fillets B' are fixed in the mould A', and the candle, after being cast therein, is placed in another mould, having a plain surface, similar to A. Or projecting colored fillets may in like manner be formed on the candle, by first casting the candle in a mould with fixed projecting fillets, and then placing the candle in a mould having corresponding recesses, or grooves.

Figure 6 shows a longitudinal section, and Figure 7 shows a plan of one arrangement for cutting the grooves upon the candle, after it has been cast in the ordinary manner.

C is a fixed mould, having the same internal form as the candle to be operated upon.

This mould has a slit, D, right along it, so that when the candle E is placed in the mould, and a cutting-tool, F, is passed along the slit, a corresponding groove will be formed in the surface of the candle.

The upper end of the candle E and of the mould C being formed hexagonal or polygonal, it will be seen that if, after cutting the groove as described, the candle is drawn out of the end of the mould, and is turned so as to bring the hexagonal end successively into different positions in the end of the mould, a succession of equidistant grooves may be cut in the surface of the

candle, and these may then be filled in with material of a different color, as before described.

If, instead of straight grooves, it is desired to cut helical grooves on the candle, the mould C has a corresponding helical slit, and is arranged so as to be capable of turning on its longitudinal axis while the cutter is passed along the slit.

Figures 8 and 9, on Sheet II of the drawings, show another arrangement of machinery for cutting the helical grooves on the candles. Fig. 8 shows a front elevation, and fig. 9 shows a plan of the same.

H is the bed of the machine, upon which are fixed the bearings I I¹ I², in an adjustable manner.

The bearings I I¹ carry the helically-grooved cylinder J, upon the end of which is the socket j, formed as shown to allow the cutter to pass freely to the extreme end of the candle.

In this socket is fixed one end of the candle K, the other end being held in the opposite socket L, supported by the bearing I².

This socket is free to turn and slide in its bearing, and is kept up to its position by means of the back spring l.

M is the sliding-bar, supported by the brackets m m.

Upon this bar is the block N, which is arranged to slide transversely in a dovetail groove on the bar, and in which block is fixed the cutter n.

This cutter is regulated according to the depth of cut required by means of the set-screw n¹ acting upon the fixed stop n², and is kept in position by means of the spring n³.

This set-screw may either be turned by the workman, at the commencement of each cut, or the screw may be provided with a star head, which, just previous to the cutter-block being released by the sliding-stop S, comes in contact with a stud, fixed so as to catch one of the points of the star-headed screw, and thus to cause it to turn round and to make the cutter advance the required distance.

Upon the sliding-bar M is also fixed the roller O, which works backward and forward in the grooves of the cylinder J, and in thus causing the cylinder to revolve, imparts rotary motion to the candle.

P is the fly-wheel, supported in bearings, as shown, and upon the axis of which is the pinion p, which gears into a spur-wheel Q, upon the axis of which is fixed the eccentric, or crank-plate q.

To this eccentric is attached one end of the connecting-rod R, shown in dotted lines in fig. 8, the other end of which is connected to the rocking-lever r, the lower end of which works on a pin attached to the base of the machine, while the upper end carries another connecting-rod r¹, the other end of which is attached to a block, r², fixed upon the sliding-bar M.

The action of the machine is as follows:

The sliding-bar, with its cutter, being placed in position for commencing the cut, as shown in the drawing, motion is imparted to the fly-wheel P, which, by means of the pinion p and spur-wheel Q, communicates motion to the crank-plate q.

This crank-plate, through the intervention of the connecting-rod R, imparts a rocking motion to the lever r, and this, by means of the connecting-rod r¹, communicates a to-and-fro motion to the sliding-bar M and cutter n, and consequently, also, by means of the roller O, a rotary motion to the grooved cylinder and the candle K.

When, by these means, the cutter has been drawn to the opposite end of the revolving candle, it will be

evident that a helical groove, corresponding in pitch, or inclination to the groove in the cylinder, will have been cut thereon, after which it is necessary that the cutter should be drawn away from the surface of the candle, in order that it may be brought back to commence the cut again.

For this purpose a sliding-stop, S, is held, by means of pins s s, upon the edge of the sliding-bar M. When the cutter arrives at the end of its cut, one end of the stop S comes in contact with the edge of the bearing I¹, and as the motion of the bar continues a little, the stop is caused to slide upon the pins s s, and, in doing so, brings an inclined surface, s¹, formed upon the upper edge of the stop, in contact with a projecting-stud t, upon the under side of the cutter-block N, and thus causes this block, with the cutter, to recede from the surface of the candle, in which position it remains until, upon the bar M, moving back to commence another cut, the other end of the sliding-stop comes in contact with the edge of the bearing I², and is thus caused to slide upon its pins in the contrary direction, and thereby releases the cutter-block, which slides toward the candle again, ready to commence the cut.

If more than one helical groove is required to be cut upon the surface of the candle, it can be readily done by turning the candle upon its axis, so as to bring a different part of its surface in contact with the cutter.

For this purpose, the socket j, which holds one end of the candle, is arranged so as to turn and be fixed in different positions upon the axis of the grooved cylinder J.

Figures 10, 11, and 12, on Sheets I and II, show candles ornamented as above described, by means of folding-moulds, the moulds being formed with projecting designs on their inner surface, corresponding with the colored designs on the candles. These designs are so arranged that they are all connected by a channel, x x x, that passes to the end of the candle, so that on running the colored material down such channel it will find its way into all the recessed designs.

Having thus described the nature of our invention, and in what manner the same is to be performed, we wish it to be understood that we in no way limit ourselves to the arrangements hereinbefore described for forming the grooves or recesses on the surfaces of the candles; nor do we claim the before-described machinery, or apparatus for effecting this operation, as forming any part of our present invention, as various other contrivances may be employed for this purpose, and we have only described the aforesaid arrangements in order to indicate some practical mode of carrying our invention into effect; but

What we claim, is—

1. Ornamenting candles, by first forming grooves, or recesses, of any desired form, upon the surfaces of candles, and then filling in such grooves with wax, stearine, paraffine, or other suitable substance, of a different color from that of the candle.

2. Forming grooves, or recessed designs upon candles, substantially as hereinbefore set forth.

In testimony whereof we have signed our names to this specification, in the presence of two subscribing witnesses, this 4th day of December, 1868.

ARTHUR FIELD.
